APPARATUS FOR DELIVERING CASTING MATERIAL UNDER PRESSURE TO DIES

Louis H. Morin, Bronx, N. Y., assignor to White-hall Patents Corporation, Bronx, N. Y., a corporation of New York

Application November 22, 1938, Serial No. 241,745

10 Claims. (CL 22—70)

This invention relates to what are known as die casting machines and particularly to what is commonly termed the gooseneck structure of the pot containing the heated casting material, from which the casting material is discharged through a nozzle at the free end of the gooseneck under pressure into suitable dies in forming pressure die castings. More particularly, the invention relates to a novel method of controlling and regulating the feed of the casting material into the gooseneck and through the discharge nozzle thereof so as to maintain the casting material in the discharge passage of the gooseneck and adjacent the discharge orifice of the nozzle thereof intermediate the injection strokes of the machine, and further in accomplishing this result by a valve constituting part of the plunger employed for pressure discharging the casting material from said nozzle. The novel features of the invention will be best understood from the following description and annexed drawings, in which one embodiment of the invention is disclosed and in which the separate parts of the device or apparatus are designated by suitable reference characters in each of the views, and in which:

Fig. 1 is a longitudinal sectional view through a melting pot of a die casting machine showing the gooseneck thereof in section.

Fig. 2 is a view similar to Fig. 1 showing only a part of the construction on an enlarged scale and with parts in a different position.

Fig. 3 is a sectional detail view of part of the structure shown in Fig. 2 and with parts in another position.

Fig. 4 is a view similar to Fig. 2 showing a modification.

Fig. 5 is a perspective view of a part of the construction shown in Fig. 1 of the drawings, and

Fig. 6 is a face view of a part of the structure shown in Fig. 2.

In the art of die casting, that is to say, the pressure feeding of a casting material into the impression of suitable dies, it has been the common practice to provide a passage in the gooseneck for admitting casting material into the chamber thereof below a piston or plunger employed for the pressure discharge of the casting material from the gooseneck, which passage is sealed in the downward movement of the plunger. However, on the upward stroke of the plunger, intermediate successive casting operations, the passage is uncovered and the casting material in the gooseneck is lowered to a level fixed by the level of material in the pot. In this operation air

is drawn into the gooseneck passage, not only by the lowering of the material in said passage, but by the suction created in the upward movement of the plunger. This method of procedure has been seemingly satisfactory in what I term slow speed casting machines, and in fact has operated with a reasonable degree of success in machines producing a successive series of castings at the rate of about two hundred per minute.

However, I have found from careful study and experimentation that regardless of the speed of operation, castings having perfect definitions are difficult to produce in accordance with this old process or method of procedure. It is the purpose of my present invention to obviate these objectionable features in the present or so-called slow speed casting machine, while at the same time providing a gooseneck construction or method of controlling and regulating the pressure discharge of the casting material so as to provide for the production of what I term high speed die castings; that is to say, the formation of a successive series of individual die castings at the rate of six hundred and fifty to eight hundred or more castings per minute, especially in the production of what are termed small die castings, the size of the casting being formed, controlling to some degree, the speed of operation of the machine.

In Figs. 1 to 3 of the drawings, one embodiment of the invention is disclosed, it being understood that the particular type and design or general structure of the melting pot employed may be constructed and designed to suit machines of various types. In Fig. 1 of the drawings, 5 represents the pot proper which is provided with an inlet passage 6 opening through the lower end thereof in the manner illustrated, so that products of combustion from a gas or other burner 7 may pass over the bottom of the pot 5 and around passages at the sides thereof and then out through a flue passage 8 having a pipe extension 9 in communication therewith. At 10 is shown an outer casing encircling the pot between which and the wall of the pot is arranged asbestos and other insulation 11, a lower cover plate 12 being employed to support the asbestos in the manner illustrated. At 13 is indicated a pyrometer bulb providing a temperature control for the heated material in the pot. All of this structure is substantially the same as that disclosed in my prior Patent #2,106,505, and as previously stated is shown simply to illustrate one adaptation of my present invention.

At 14 I have shown a gooseneck having a lower casing portion 15, a chamber 16 therein opening 55

upwardly through a perpendicular tube 17 in which is seated a bushing 18 of any suitable material. In some uses of the invention, the bushing 18 will be composed of a hard material, such 5 for example as tungsten carbide or tantalum carbide, in accordance with the teachings in my prior application, Serial No. 91,479, filed July 20, 1936, which has since matured into Patent No. 2,145,553 of January 31, 1939.

10 At one side of the casing 15 is an upwardly and laterally extending tube 19 having a passage 20 therein which opens into the chamber 16 through a port 21 in the bushing 18. The upper end of the tubular extension 19 is beveled as seen 15 at 22 to seat in a suitable bearing 5a in the pot 5 and to be held therein in any desired manner preferably so as to provide quick attachment and detachment of the gooseneck 14 as a whole from the pot whenever desired. Secured in the outer 20 upper end of the extension 19 is a nozzle 23 having a discharge passage as at 24. By employing a nozzle 23 which is detachable with respect to the gooseneck extension 19, this nozzle may be 25 readily replaced or nozzles of different sizes or having different size discharge passages 24 can be employed.

The casing 15 or the tubular portion 17 thereof is provided with a port 25 which places the chamber 16 in communication with the casting material 26 in the pot through a port or aperture 27 formed in the bushing 18 it being understood that various metals or metal alloys are used as the casting materials referred to.

30 At 28 is shown the plunger employed for the pressure discharge of the casting material. The lower end of this plunger is provided at one side with a downward projecting circumferentially segmental extension 29 which forms a valve end on said plunger which is provided with a port 30 35 therein adapted to register with the port 21 as later described. The lower end 28a of the plunger 28 at the opposite side of the valve extension 29 also functions as a valve controlling the opening and closing of the port 27 in the complete cycle of operation of the plunger. It will of course be understood that the plunger 28 is maintained in the circumferential position illustrated 40 in the drawings by suitable means for keying the same or by the means employed for coupling the same with its operating mechanism, all of which forms no particular part of the present invention.

45 It will be understood that the chamber 16 extends into the bushing 18 and is sealed by the plunger 28, depending upon the position thereof 50 in the bushing. With the construction shown, the passage 20 in the bore of the tube 19 forms a storage chamber which is independent of the chamber 16 but is placed in communication with the latter through ports 21, 30 when brought into 55 registering position. It is by virtue of this construction that the casting material is held in the passage 20 to maintain the casting material at the upper end of the passage 20 adjacent the discharge port 24 of the nozzle, as is indicated at 60 65 26a.

In Figs. 1 and 2 of the drawings, I have shown 70 diagrammatically, one of the die parts 31 of a pair of relatively movable dies, a face view of the die part being illustrated so as to show the impression 32 therein and the gate or admission passage 33. A core pin 34 is also indicated as arranged between adjacent surfaces of the two die parts so that the casting may be formed thereon and the core pin used to eject the casting from 75 the impression 32 and whereby the same may be

stripped off by engaging the lower surface 31a of the die part 31 in the manner indicated in Fig. 2 after which the core returns to its normal position. In Fig. 2 of the drawings, the nozzle 23 is indicated as engaging the surface of the die 31, 5 but in some types of machines, the nozzle may be moved toward and from the die intermediate the casting operations. In some forms of construction, the nozzle moves with one of the die parts in the separation thereof to maintain the passage 24 10 substantially closed or sealed.

In the operation of my improved gooseneck or discharge device, it will be understood that in the extreme upward movement of the plunger 28, the same will assume a position substantially similar 15 to that illustrated in Fig. 2 wherein the lower end 28a of the plunger has fully uncovered the port 27 to allow casting material to enter the chamber 16 therethrough and through the port 25; whereas the port 21 is sealed by the valve extension 29 on 20 the plunger which supports the column of the casting material in the passage 20 substantially as is indicated in Fig. 2, assuming that the machine has been in operation.

In the operation of pressure discharging the 25 casting material, the plunger 28 moves downwardly, and in this operation the port 27 is shut off by the lower end 28a. At the same instant the port 30 is brought into a slight registration with the port 21, and beginning with this period, 30 the pressure discharge of the casting material becomes effective and some of the material in the chamber 16 is forced into the passage 20, and the material in said passage is discharged under pressure through the discharge port 24 of the nozzle 35 into the impression 32 of the die through the gate or admission passage 33. It will be understood that the nozzle has been brought into registering alignment with the dies or the gate 33 prior to the above operation. On completing the downward 40 stroke of the plunger, the ports 21, 30 will never be fully closed, or in other words will be at least partially open as is indicated in Fig. 3 of the drawings. In the upward movement of the plunger, the port 21 will be first closed by the valve 45 extension 29 and then the port 27 immediately opened to admit a new charge of casting material into the chamber 16 to replace the material previously discharged therefrom in the downward movement of the plunger. In the above opera- 50 tion, it will be understood that there will be a slight drop of the casting material in the passage 20 which will be sufficient to simply clear the discharge port or orifice 24 of the nozzle. However, in view of the proposed high speed operation 55 of the plunger, this condition amounts to a momentary one, and the drop of casting material in the passage 20 will be hardly noticeable or detectable.

In the above described operation, it will be understood that the ports or passages 21, 30 come 60 into full registering position with each other in the upward or return stroke of the plunger, but this takes place while the plunger seals the passage 27, the latter being open instantly upon the 65 full closure of the passage 21. Thus the valve 29 will check and prevent return of the casting material aside from the slight drop of the material in the passage 20 due to the momentary registration of the passage 30 with the passage 21 70 in the quick upward movement of the plunger 28.

It will of course be understood that when the casting material is pressure injected into the cavity or impression 32 of the dies, the same is chilled or solidified therein, and as the nozzle is held 75

momentarily in registering position with the dies, the solidified casting material will act as a seal aiding and preventing an appreciable drop of the casting material in the bore or passage 20 which might be assisted, to some degree, by the suction created in the upward movement of the plunger 28, when the ports 21, 30 are in registering position, in this upward stroke. Here again it is to be borne in mind that the high speed operation of the machine measures these various factors in minute periods, especially when the plunger is operating at the rate of six hundred and fifty or more operations per minute. It will also be apparent in this connection that such an action upon the column of material in the passage 20 is cut off instantly upon sealing the passage 21 with the valve 29 as is illustrated in Fig. 2 of the drawings.

It will be understood that, in the conventional methods of die casting, material was permitted to drop in the discharge passage of the goose-neck to an appreciable degree, and the column of air in the passage above the material would have to be first displaced through the dies or from the impression 32 of the die to insure the formation of a reasonably accurate casting, that is to say a casting having a reasonably good definition of the cavity. With my construction and method, this undesirable air column is reduced to a minimum if not entirely dispensed with, and insures the formation of die castings having substantially accurate definitions and finish throughout. It will thus be seen that the present invention is adaptable for use in connection with all types and kinds of die casting machines; that is to say machines of the slow as well as the high speed type. In all cases, more perfect or more accurate castings are formed, and at the same time considerable time and labor is saved which has been heretofore necessary in the cleaning out, repair and/or replacement of goosenecks or gooseneck parts in the effort of maintaining the same in a proper operative condition.

It has been a practice to utilize long rods arranged in the discharge passage, such as the passage 20, of a gooseneck to control and regulate at least to some degree, the discharge of the casting material and to facilitate the use of a relatively large diameter in such bore or passage. However, in the use of rods of this type, the same become oxidized from time to time and must be removed and replaced in order to provide successful casting operations of the machine. Here again, with my present invention, I may maintain a relatively large passage 20 and dispense entirely with the use of such rods, and thereby dispense with and eliminate the nuisance as well as the loss of time and inconvenience in repeatedly removing and replacing such rods to say nothing of the saving in the increased production which is obtained by eliminating the necessity for such intermittent repairs or replacements. By maintaining the passage 20 of the gooseneck substantially filled with the material at all times, I eliminate oxidation in the passage and thus provide long life for the entire gooseneck structure.

It will of course be understood that the size of the various ports and passages and particularly the port 30, may be increased or decreased to suit the particular type and kind of casting to be formed, or in other words to compensate for the amount of casting material to be discharged into a given die.

In some instances where it is desirable to substantially eliminate any drop whatever of the material in the passage 20 or the nozzle, the plunger 28 may be given a rotary reciprocating movement so that in moving from its lowermost position to the uppermost position, the passage 30 may be moved out of registering position with the passage 21 and then return to register with the passage 21 on the next down stroke of the plunger. This operation can be performed by any of the common known means. In fact, any means, apart from the particular manner herein described for operating the plunger, may be employed to accomplish this particular result in carrying out my improved method which is dependent upon the sealing or closing of the passage 21 after the discharge of casting material from the nozzle, that is to say intermediate successive injection strokes of the plunger.

It will be understood that by sealing the passage 21, intermediate the injection strokes of the plunger, the possibility of drawing an excess amount of air into the passage 20 or the building up of an internal pressure in this passage, is obviated, and the degree of controlling this seal may be, as originally described, in conjunction with the disclosure, or by incorporating the rotary movement to the nozzle or the valve 29 thereof to bring the ports 21, 30 in non-registering position at the end of the injection stroke 30 and prior to the upward stroke of the plunger to effect a substantially positive seal of the passage 21 in said upward stroke of the plunger.

In certain operations of casting machines, particularly of the slower type, that is to say those operating at two hundred revolutions or strokes per minute and less, it may be desirable to incorporate a separate heating unit, preferably of the electric type on the nozzle 23, for example in accordance with the teachings in Patent No. 2,026,904 granted January 7, 1936, so as to maintain the casting material at the desired temperature within said nozzle and prevent any question of solidification thereof. However, in high speed machines, this of course will not be essential in that the material is being moved so fast that it would have no opportunity to become chilled or solidified.

My improved apparatus or device and the novel method of injection molding or casting as herein set forth may be said to be an air-free or substantially air-free discharge of the heated casting material. It will be understood in this connection that in certain forms of the device as hereinbefore described, the casting material may be held at the discharge end of the orifice or passage of the nozzle by maintaining a complete seal of the discharge passage intermediate the successive operations of the plunger. It might also be said that the desired result is produced by providing means for checking the backward suction on the column of casting material in the discharge passage in the upward stroke of the plunger, which, if left unchecked in a high speed machine, might actually result in the lowering of the material in the passage to a degree below the level of the material in the supply tank or pot and would result in the faulty or improper functioning of the machine.

In the present illustration, the injection nozzle is shown arranged above a level of casting material in the pot or receptacle, notwithstanding the fact that the receptacle is of sufficient height to provide for a higher level of the material therein. It is apparent, however, that my in-

vention will operate regardless of the relative positions of the nozzle and the receptacle or the level of casting material in the receptacle, in that its operation is dependent upon the controlling valve and not upon the level of material in the pot. In this connection it is also to be understood that in various types and kinds of casting machines, different forms and types of goosenecks and discharge nozzles are employed.

10 In considering the gooseneck construction disclosed, this device may be said to have a main storage chamber as at 16, and a supplemental storage chamber at 20. The latter forms the storage for material to be directly transmitted 15 to the die and arranged for the so-called air-free discharge of the material into the die, whereas the main storage chamber acts as the pump or pressure chamber which replenishes the supplemental storage chamber with a supply of material consistent with that displaced therefrom 20 for injection into the mold cavity.

In Figs. 4 to 6 inclusive, is shown a slight modification, particularly in the construction of and manner of controlling the operation of a 25 plunger 35. This plunger is arranged and operates in a gooseneck structure 14 similar in all respects to that shown in Figs. 1 and 2, therefore like references will indicate like parts and a detail description of the gooseneck structure 30 need not here be repeated. In other words, the same sleeve, bushing or liner 18 is arranged in the tube 17 and is provided with the ports 21, 27 to register with the ports or passages 20, 25 respectively.

35 The plunger 35 differs from the plunger 28 in the provision of means for adjusting the plunger vertically so as to control registration of a spirally arranged port 36 with respect to the port 21 to provide an accurate desired adjustment in 40 registration with the port 21, consistent with the registration of the port or passage 37 with the port 27. In the construction shown, the passages 36, 37 are in the form of grooves on the outer surface of the plunger adjacent the lower 45 end 38 thereof. The groove 36 is spiralled downwardly whereas the groove 37 is arranged circumferentially, maintaining throughout the length thereof an equal distance with respect to the lower end 38 of the plunger. The grooves 36 and 37 are placed in communication with or open 50 through the end 38 in feed grooves 36a, 37a so as to permit the passage of the casting material from the chamber 16 into the grooves 36, 37.

To adjust the plunger 35 vertically in the 55 proper setting thereof, a split clamp ring 39 is arranged on the upper end of the plunger and is clamped in position by a screw or bolt 40 passed through the split ends 41 thereof, the ring carrying at one side a projecting lug 42 which operates 60 in a channel 43 arranged upon the gooseneck or supported in any other desired manner so as to key the ring 39 against rotation. The upper end of the plunger 35 has an internally threaded bore 44 to receive an extension rod 45 which places 65 the plunger in operative engagement with the means for actuating the same. The rod 45 is retained against rotation by the means usually employed. It will thus be seen that by loosening the clamp collar 39, the plunger 35 may be raised 70 and lowered on the rod 45 and then clamped and keyed against further rotary movement.

In order to indicate to the operator the degree of adjustment made, for the proper setting of the plunger, the plunger will be provided with 75 an arrow or other mark 46 which is adapted to

register with suitable scale markings 47 on the lower beveled surface of the ring 39. In this way a more or less micrometer adjustment may be indicated to the operator.

It will be understood that the port or passage 5 37 is substantially equivalent to the lower surface 28a of the plunger 28 in controlling the opening and closing of the port 27. The passage 37 is made sufficiently long circumferentially to compensate for any slight adjustment 10 which may be made on the plunger 35. This adjustment is primarily to set or fix the relationship of the ports or passages 36, 37 with respect to the ports 21, 27 so as to satisfy the requirement especially in making different types and 15 kinds of castings or castings of different sizes in a single machine, and further to provide accurate timing between the closure of one port and opening of the other port in accomplishing the desired results heretofore expressed in detail. A 20 device constructed in this manner will obviate the necessity of exact duplication of parts especially in the replacement of plungers, and further will avoid the necessity of very accurate original formation of the respective plungers. It will be 25 understood that the groove 36 will be made with respect to the groove 37 to produce substantially the desired result when the ports 21, 27 register with the central portions of said grooves, so that the plunger may be raised or lowered a slight 30 degree in providing a slower or quicker registration of the groove 36 with the port 21 in the downward movement of the plunger. In this connection it will be understood that the position of the parts as seen in Fig. 4 is substantially 35 the same as that shown in Fig. 1. In other words, the plunger is in an intermediate position in the downward stroke thereof, where the port 27 is closed and the port or passage 36 is beginning to register with the port 21.

40 It will also be apparent that the angularity of the port or passage 36 with respect to the port 21 in addition to providing the control adjustment also minimizes the degree of opening between the port and passage especially at the 45 initial opening period.

Having fully described my invention, what I claim as new and desire to secure by Letters Patent is:

1. In a gooseneck for die casting machines, said 50 gooseneck having a discharge passage with a nozzle discharge at one end thereof, a storage chamber at the other end of the passage, a port placing the storage chamber in communication with a source of supply of casting material, another port placing the storage chamber in communication with the discharge passage, a plunger movable in said gooseneck for pressure discharging casting material from said storage chamber through the discharge passage, means 60 on the plunger controlling the opening and closing of the first named port, other means on the plunger placing the storage chamber in communication with the second named port, and means for adjusting the plunger to regulate the 65 timing of the registration of the last named means with said second named port.

2. In a gooseneck for die casting machines, said 70 gooseneck having a discharge passage with a nozzle discharge at one end thereof, a storage chamber at the other end of the passage, a port placing the storage chamber in communication with a source of supply of casting material, another port placing the storage chamber in communication with the discharge passage, a plunger 75

er movable in said gooseneck for pressure discharging casting material from said storage chamber through the discharge passage, means on the plunger controlling the opening and closing of the first named port, other means on the plunger placing the storage chamber in communication with the second named port, means for adjusting the plunger to regulate the timing of the registration of the last named means with 5 said second named port, said last named means including a clamp collar for engaging the plunger to retain the same in different positions of adjustment, and means on the plunger and collar for indicating degrees of adjustment of said 10 plunger.

3. A plunger for pressure discharging casting material from the gooseneck of a melting pot, the discharge end portion of said plunger having a 20 pair of independent passages, one passage controlling the admission of casting material into the gooseneck from a source of supply, the other passage controlling the discharge of casting material from the gooseneck, both passages extending circumferentially of the plunger, the second 25 named passage being arranged spirally, and means at the other end portion of the plunger for adjusting the same longitudinally of its support and operating means and for retaining the same in different positions of adjustment in controlling 30 registration of the passages with the respective ports in the movement of the plunger in said gooseneck.

4. A gooseneck of the class described comprising a cylinder, a plunger movably mounted in the 35 cylinder, the cylinder having longitudinally and circumferentially spaced intake and discharge ports, the intake port introducing material, from a source of supply, into the cylinder below said plunger, the plunger descending in the cylinder 40 being adapted to force casting material therein through the discharge port of the cylinder, means actuated by the plunger sealing the discharge port in the raised position of the plunger and while the intake port is open, means including the 45 last named means whereby in the closure of the intake port, in the downward movement of the plunger, the discharge port is immediately opened to the cylinder in pressure discharging the casting material through said discharge port, and adjustable means for setting the relationship of 50 closing the intake port with respect to the opening of the discharge port in controlling the pressure discharge of casting material from said cylinder.

5. In a device for transmitting casting material from a source of supply to a discharge nozzle for admission into the impression of relatively movable dies, a cylinder in said device, an intake port placing said cylinder in communication with the 55 storage supply of casting material, another port for placing said cylinder in communication with the discharge nozzle, a plunger operating in the cylinder to pressure discharge casting material therefrom through the discharge port to said nozzle, means on the plunger controlling said intake and discharge ports to open the discharge port to the cylinder immediately upon the closing of the intake port to said cylinder, and adjustable means

for accurately regulating the relative closing and opening movements of said intake and discharge ports.

6. In devices for pressure discharging heated casting material into relatively movable dies, a 5 plunger for pressure discharging said heated material from the device, said plunger having circumferentially arranged and spaced intake and discharge passages controlling the intake and discharge of casting material with respect to said 10 device, and said plunger being adjustable to control the relative closing of the intake and opening of the discharge in the pressure discharge of the casting material by the operation of said plunger.

7. In devices for pressure discharging heated casting material into relatively movable dies, a plunger for pressure discharging said heated material from the device, said plunger having circumferentially arranged and spaced intake and 20 discharge passages controlling the intake and discharge of casting material with respect to said device, said plunger being adjustable to control the relative closing of the intake and opening of the discharge in the pressure discharge of the 25 casting material by the operation of said plunger, at least one of said passages being spirally arranged upon said plunger, and means for indicating different positions of adjustment of said plunger.

8. In a gooseneck of the class described comprising a cylinder having an intake port registering with a source of supply and a discharge port registering with the discharge passage of the gooseneck, a plunger longitudinally movable and 35 rotatably adjustable in said cylinder, means on said plunger controlling said intake port, other means on said plunger controlling said discharge port, said last named means comprising a spirally arranged passage adapted to register with said discharge port, and means on said plunger 40 for gaging and setting the rotary adjustment thereof to provide opening of each of said ports instantaneously upon the closing of the other of said ports in the longitudinal movement of the plunger.

9. A die-casting machine comprising a cylinder having a closed end and a plunger reciprocable in said cylinder, said cylinder having outlet and inlet ports adjacent said closed end, said inlet port being opened and closed by movement of said plunger, a valve member on said plunger arranged to close said outlet port and to open it only when said inlet port is entirely closed by said plunger, and means to adjust said valve 55 member lengthwise of the cylinder, for the purpose set forth.

10. A die-casting machine comprising a cylinder having a closed end and a plunger reciprocable in said cylinder, said cylinder having outlet and inlet ports adjacent said closed end, said inlet port being opened and closed by movement of said plunger, a valve member on said plunger arranged to close said outlet port and to start to open it at the instant that closing of the inlet 60 port is completed, and means to adjust said valve member lengthwise of the cylinder, for the purpose set forth.

LOUIS H. MORIN.
